US0D1050746S

(12) **United States Design Patent** (10) **Patent No.:** **US D1,050,746 S**
(45) **Date of Patent:** **** Nov. 12, 2024**

(54) **INVERSION BENCH EQUIPMENT**

(71) Applicant: **Xiamen Caminz Technology Co., Ltd.**, Fujian (CN)

(72) Inventor: **Haiyu Xie**, Fujian (CN)

(73) Assignee: **Xiamen Caminz Technology Co., Ltd.**, Fujian (CN)

(**) Term: **15 Years**

(21) Appl. No.: **29/952,868**

(22) Filed: **Jul. 18, 2024**

Related U.S. Application Data

(62) Division of application No. 29/921,941, filed on Dec. 20, 2023, now Pat. No. Des. 1,041,598.

(57) **CLAIM**

The ornamental design for an inversion bench equipment as shown and described.

DESCRIPTION

FIG. 1 is a front elevation view of inversion bench equipment, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a first perspective view thereof; and,

FIG. 8 is a second perspective view thereof.

1 Claim, 8 Drawing Sheets
